AIR-MOVING DEVICE

Carl Martin Buttner, Memphis, Tenn., assignor
to Hunter Fan and Ventilating Company, Inc.,
Memphis, Tenn., a corporation of New York

Application June 17, 1949, Serial No. 99,680

12 Claims. (Cl. 98—116)

1

This invention relates to improvements in air-moving devices. More particularly this invention relates to an improved mechanism for operating the louvers of an air-moving device.

It is therefore an object of the present invention to provide an improved operating mechanism for the louvers of an air-moving device.

In the operation of the louvers of an air-moving device, it is desirable to be able to move the louvers to and from open position without necessitating the exercise of dexterity or skill on the part of the operator. Where this is done, children as well as adults can safely open and close the louvers. However, in using some prior louver-operating mechanisms the operator had to align the operating cord or chain with a slot and then move that cord or chain into that slot. In other instances the operator of the louver-actuating mechanism had to have a rather delicate sense of touch because he had to "feel out" one of a number of possible settings for the louvers. These prior louver-actuating mechanisms are quite workable where the operators have keen vision and have good manual dexterity; but not all potential operators of those mechanisms have those qualifications. Moreover, the louver-actuating mechanisms are frequently disposed over the operator's head; requiring the operator to have a good sense of equilibrium as well.

For these various reasons, prior louver-actuating mechanisms for air-moving devices are objectionable. The present invention obviates these objections by providing a simple louver-actuating mechanism which can be operated by even the most unskilled persons. That mechanism responds to a downward pull on its cord or chain to lock the louvers open, and then responds to a second downward pull on that cord or chain to permit the louvers to close. With such a mechanism there is no need of keen vision, good dexterity, or stable equilibrium; all that is needed is the desire to actuate the mechanism and a downward pull on the cord or chain. It is therefore an object of the present invention to provide a louver-operating mechanism that responds to a downward pull on its cord or chain to lock the louvers open, and that responds to a second downward pull to permit the louvers to close.

The louver-operating mechanism provided by the present invention is sturdy and rugged, and it has a spring between the cord or chain and the latching elements. Thus the mechanism can withstand strong forces exerted thereon, and the spring will yield and limit the size of the forces

2

that can be applied to the operating mechanism. It is therefore an object of the present invention to provide a sturdy and rugged louver-operating mechanism which has a spring between the cord or chain and the latching elements.

The louver-actuating mechanism provided by the present invention has a movable arm which carries a rotatable ratchet with alternate deep and shallow notches. The alternation of the deep and shallow notches enables a pawl to engage or be held away from a locking shoulder on the movable arm. Thus the pawl can enter the deep notches of the ratchet to engage the locking shoulder and hold the louvers open; or it can enter the shallow notches of the ratchet and be held away from the locking shoulder and permit the louvers to close. The louver-operating mechanism is so arranged that alternate downward pulls on the cord or chain will present a deep notch and then a shallow notch to the pawl. It is therefore an object of the present invention to provide a louver-actuating mechanism with a movable arm that carries a rotatable ratchet with alternate deep and shallow notches.

25 The louver-operating mechanism provided by the present invention has a spring disposed above and at an angle to the louvers. This spring provides an initial opening force on the louvers, but it is so set relative to the louvers that it resists movement of those louvers to fully opened position. Consequently, the one spring provides an initial opening force and an initial closing force for the louvers. Those forces are quite important because they start the louvers moving toward and away from open position, and thus they assist the actuating-mechanism to effect the desired movement of the louvers. It is therefore an object of the present invention to provide a spring that provides an initial opening and an initial closing force for louvers.

30 The pawl, which is used to engage the notches in the ratchet and the locking shoulder on the movable arm, will move slightly as the ratchet and arm move relative to it. However, that ratchet will be biased to ratchet-engaging position by a spring and will normally be in ratchet-engaging position. In the event of a fire in the building or structure ventilated by the air-moving device, a second spring will come into action and move the pawl wholly out of engagement with the ratchet and the movable arm; thus freeing the arm for movement to louver-closing position. The second spring is normally kept from 35 acting by a heat-responsive link; but that link

will soften and permit the second spring to move the pawl whenever a fire occurs. This is very desirable because it minimizes drafts that would feed the fire.

The louver-actuating mechanism of the present invention engages the switch arm of a mercury switch and causes that arm to tilt the switch to "on" position. However, that switch arm is not positively linked to the louver-actuating mechanism; and thus if the louver-operating mechanism were to break or to shift out of engagement with the switch arm, the switch could move to "off" position. Such movement is assured by a spring which acts upon the switch arm and biases it to "off" position. Such an arrangement is very desirable because it keeps the motor of the air-moving device from overheating due to operation when the louvers are closed. It is therefore an object of the present invention to provide a switch arm movable independently of the louver-operating mechanism and to provide a spring which acts directly upon that arm to bias it to "off" position.

In many louver-operating mechanisms the manufacturing tolerances for the pivots for the louvers permit the louvers to be shifted by the air passing through the louvers. This shifting of the pivots causes noise, and that noise will be amplified by and radiated from the large surfaces of the louvers. Such noise is very objectionable, and it is completely avoided by the construction provided by the present invention. That construction includes a stiff spring which bears against a pivot on each and every louver, and which urges those pivots into intimate engagement with the pivot supports; thus minimizing shifting of the pivots. It is therefore an object of the present invention to provide a stiff spring that biases a pivot on each and every louver into intimate engagement with the pivot supports.

The stiff anti-rattle spring provided by the present invention is preferably threaded through notches formed in the casing of the air-moving device. Those notches will parallel a line passing through the pivots of the various louvers, and they will tend to hold the spring parallel to although spaced from the line extending through the pivots. Consequently the spring must be distorted to pass around the pivots, and that spring will tend to restore itself; and in doing so it will provide a steady and constant force on the pivots.

Other and further objects and advantages of the present invention should become apparent from an examination of the drawing and accompanying description.

In the drawing and accompanying description a preferred embodiment of the present invention is shown and described but it is to be understood that the drawing and accompanying description are for the purposes of illustration only and do not limit the invention and that the invention will be defined by the appended claims.

In the drawing,

Fig. 1 is a cross-sectional side view of an air-moving device that is made in accordance with the principles and teachings of the present invention.

Fig. 2 is an enlarged side elevational view of the casing for the louver-operating mechanism provided by the present invention.

Fig. 3 is a partially-broken, cross-sectional end view of the casing and louver-operating

mechanism provided by the present invention.

Fig. 4 is a larger side view of a portion of the angle and spring shown in Fig. 1, and

Fig. 5 is a side elevational view of a ratchet and part of a rotatable arm used in the air-moving device shown in Figs. 1-3.

Referring to the drawing in detail, the numeral 10 denotes a housing for an air-moving device. That housing is provided at its upper end with a Venturi ring 12 which defines a large circular opening at the center of the housing 10. A number of resilient mountings 14, which are stressed in compression and shear, are secured to the upper surface of the housing 10. These mountings are generally annular in form and each of them is disposed adjacent a circular opening, not shown. The mountings 14 surround and are secured to stanchions 16, and they enable those stanchions to move up and down and from side to side relative to the housing 10. The weight of the stanchions 16, and the apparatus supported thereby, is resisted by shear and compressive forces within the mountings 14.

The stanchions 16 carry a horizontally-disposed bearing support 18, and that bearing support carries a sleeve bearing 20 adjacent the center thereof. A shaft 22 is disposed and held within the bearing 20, and that shaft carries a fan hub 24 at the lower end thereof. Four blades 26 are secured to the fan hub 24, and those blades rotate within the Venturi ring 12 to move air relative to that Venturi ring. A pulley 28 is provided at the upper end of shaft 22, and that pulley receives a belt 30 which is driven by a pulley 31 on the shaft of motor 32. The motor 32 is secured to the bearing support 18, and it is disposed adjacent one of the stanchions 16. Electrical leads 34 extend from the motor 32, and those leads extend downwardly through housing 10 to the vicinity of the louver-operating mechanism.

The housing 10 has an angle 36 disposed along two of the opposite edges thereof; only one of the angles being shown in the drawing. The two angles 36 are drilled to receive the ends of a plurality of horizontally spaced rods 38. The rods 38 support louvers 40; the louvers 40 being secured so tightly to the rods 38 that the rods 38 and the louvers 40 rotate together. Each of the louvers 40 has a projection 42 thereon, and each of the projections 42 is pivoted to an actuating rod 44. The actuating rod 44 thus holds all of the louvers 40 for conjoint rotation about their pivot rods 38; and that rod will move both vertically and horizontally as the louvers 40 rotate to and from closed position.

An extendible spring 46 is secured to the actuating rod 44 adjacent one end thereof, and the other end of that spring is attached to the housing 10 at a point above and to the right of the rod 44. Since the rod 44 must move upwardly in opening the louvers 40, the securement of the other end of spring 46 to the housing 10 at a point above rod 44 enables that spring to provide an initial opening force on louvers 40. Since the rod 44 must move to the left in opening the louvers 40, the securement of the other end of spring 46 to the housing 10 at a point to the right of rod 44 enables that spring to provide an initial closing force on the louvers 40. Thus, spring 46 performs the dual function of helping to open and helping to close the louvers 40. In moving from open to closed position the louvers 40 subtend an angle of approximately ninety (90) degrees, and the direction

of action of spring 46 is always within that ninety (90) degree angle.

A plurality of notches 48 are provided in the angles 36 secured to housing 10; and springs 50, preferably of piano wire, are threaded through those notches. There are preferably two springs 50, one for each angle 36; and those springs are threaded through the notches 48 in such a way that they alternately pass through a notch and over a pivot rod 38. The notches 48 define lines that are parallel to but are spaced below the lines defined by the ends of the pivot rods 38; and the springs 50 tend to lie in the lines defined by notches 48. In being passed over the rods 38 the springs 50 are distorted, and they tend to restore themselves to the lines defined by notches 48. In doing so, the springs 50 hold the pivot rods 38 tightly against the angles 36; thus taking up all slack due to manufacturing tolerances. As a result, the springs 50 minimize all tendencies of the louvers 40 to rattle and make noise.

A casing 52 is provided adjacent one wall of the housing 10, and that casing supports and largely encloses the louver-actuating mechanism provided by the present invention. The casing 52 has two arcuate slots 54 and 56 therein; and slot 56 is dimensioned to receive a pin 58. This pin has a connecting rod 60 secured to the front thereof, and that connecting rod is pivotally secured to the actuating rod 44 by a pin 62. A dog 64 is secured to the rear of pin 58, and that dog rotates relative to the pin. Dog 64 is biased for rotation in a counter-clockwise direction about pin 58 by the spring 66. One end of the spring 66 bears against a notch in the end of the dog 64, and the other end of the spring 66 is held in the slotted rear end of the pin 58.

The pin 58, dog 64, and spring 66 are mounted on a rotatable arm 68 which is secured to the casing 52 by a pivot 70. This pivot permits the arm 68 to be rotated relative the casing 52, and the arm 68 is dimensioned so the pin 58 will move in the slot 56. A pivot 72 is secured to the free end of rotatable arm 68; that pivot being disposed in register with the arcuate slot 54, and extending through that slot. The rear end of the pivot 72 rotatably supports a ratchet 74 which is provided with alternate deep and shallow notches. The notches of ratchet 74 are so directed that they can be engaged and held by the free end of dog 64; the spring 66 biasing that dog into engagement with the notches of ratchet 74.

A chain 77 is provided to apply opening forces to the louver-operating mechanism, and that chain is connected to pivot 72 by means of extensible spring 76. In the event the pull on chain 77 is unusually strong or is continued unduly, no harm can come to the louver-operating mechanism because the spring 76 will yield before the force on pivot 72 becomes excessive. In this way, the present invention prevents injury to the louver-operating mechanism, even where that mechanism is operated by unskilled persons.

A pivot 78 is secured to the casing 52 at a point above slot 54, and that pivot rotatably supports a pawl 80. The free end of the pawl 80 is located adjacent the ratchet 74, and it can engage the alternate shallow and deep notches of that ratchet. Whenever the free end of pawl 80 is in engagement with one of the deep notches of ratchet 74, it will be in engagement with the locking shoulder 69 on the rotatable arm 68. However, whenever the free end of pawl 80 is in en-

gagement with one of the shallow notches of ratchet 74, it will be held above and out of engagement with that locking shoulder. The locking shoulder 69 is disposed to the right of a gently rounded projection on the free end of arm 68. A spring 88 has one end thereof secured to a stud 84 on pawl 80 and has the other end thereof secured to stud 86 on casing 52, and that spring biases pawl 80 into engagement with the notches of ratchet 74.

An opening 82 is provided in the casing 52 adjacent the upper end of pawl 80, and that opening receives the stud 84 on pawl 80. The diameter of stud 84 is smaller than the diameter of opening 82; consequently stud 84 can move freely in opening 82 as the pawl 80 moves relative to the ratchet 74. Spring 88 normally holds stud 84 adjacent the left hand side of opening 82, but that stud will move toward the other side of opening 82 when the arm 68 moves the ratchet 74 to the left past the free end of pawl 80. That stud will also be moved to the right side of opening 82 if a fire occurs adjacent the air-moving device; heat-responsive link 92 softening and permitting spring 96 to tighten cable 94 and pull stud 84 to the right of opening 82. Ordinarily, the heat-responsive link 92 will be intact and will resist the forces in spring 96; that spring being extended between the right hand end of link 92 and the stud 94 which is secured to casing 52. At such times, the left hand end of link 92 will be held by stud 90 on casing 52, and the cable 94 will be free of tension. However, when the link 92 softens, the right hand end thereof will be freed from the left hand end thereof and will move under the action of spring 96. In doing so it will tighten cable 94 and will pull stud 84 to the right side of opening 82. This rotates pawl 80 completely out of contact with ratchet 74, thus freeing arm 68 for movement to louver-closing position.

A portion of the top of casing 52 is bent outwardly to provide a section 98 of increased depth to receive mercury switch 110 and the upper end of switch arm 102. That arm rotates about a pivot 100 secured to the rear of the casing 52; and it is biased for rotation in a counter-clockwise direction by spring 106 which is held by stud 104. Stud 104 receives one end of spring 106; that spring passing around pivot 100 and then being slipped behind switch arm 102. Spring 106 normally holds switch arm 102 in the "off" position; but switch arm 102 is so dimensioned and disposed relative to pin 58 that the pin 58 will strike the lower end of arm 102 and move the switch 110 to "on" position. Spring 106 is strong enough to hold the switch arm 102 in the "off" position when the pin 58 does not engage arm 102, but it will yield and permit pin 58 to move arm 102 to the "on" position. The switch 110 is held by a yoke 108 secured to the upper end of the arm 102, and the leads 34 from the motor extend to the switch 110 and to an electrical outlet, not shown.

When the louvers 40 are in closed position, the entire and combined weight of louvers 40, actuating rod 44, connecting rod 60, movable arm 68, and ratchet 74 will tend to respond to gravitational pull and hold the louvers closed. While spring 46 provides a force biasing the louvers out of closed position, it cannot alone cause opening of those louvers. While the louvers 40 are in open position, as shown in Fig. 1, the centers of mass of each of the louvers 40, actuating rod 44, con-

necting rod 60, movable arm 68 and ratchet 74 will be displaced above their closed positions; and all that is needed to close the louvers 40 is to incline them to the right of the vertical. The spring 46 will provide that inclination.

When the louvers 40 are in closed position, the movable arm 68 will be adjacent the right hand ends of the arcuate slots 54 and 56. When the louvers 40 are to be opened, a downward pull will be applied to the chain 77; and that pull will be transmitted around pulley 75 and through spring 76 to the pin 72. That pull will cause the arm 68 to rotate in a counter-clockwise direction about pivot 70, and such rotation will move the actuating rod 44 upwardly and to the left; spring 46 assisting such movement. The movement of rod 44 will cause each of the louvers 40 to open. As the arm 68 continues to rotate in a counter-clockwise direction the gently rounded projection on the end of arm 68 will engage and pass under the free end of the pawl 80; that projection acting as an inclined plane to raise the free end of pawl 80. That free end of pawl 80 will drop into a shallow notch of ratchet 74, will ride along the next inclined face of ratchet 74, and will finally drop into a deep notch of ratchet 74. The frictional engagement between pawl 80 and the inclined faces of ratchet 74 will not rotate that ratchet in a clockwise direction, because dog 64 prevents any and all such rotation. Further counter-clockwise movement of arm 68 will be resisted by engagement of pin 58 with the left hand end of slot 56; the pawl 80 being purposely set adjacent the ends of slots 54 and 56 so only two notches pass under pawl 80 when arm 68 is moved to the lefthand ends of slots 54 and 56.

The pull on the chain 77 can then be released, and the spring 46 will then act through actuating rod 44 and connecting rod 60 to pull arm 68 in a clockwise direction until the pawl 80 engages and holds the locking shoulder 69 on arm 68. Thereafter, until another downward pull is applied to chain 77, or until a fire occurs, the pawl 80 will hold arm 68 against louver-closing movement. As the arm 68 moved in the counter-clockwise direction, the pin 58 thereon engaged switch arm 102 and moved the switch 110 to "on" position. The louvers 40 will thus be held open and the air-moving device will be energized.

In the event of a fire in the vicinity of the air-moving device, the heat from the fire will soften heat-responsive link 92. Thereupon, the spring 96 will pull the right hand portion of link 92 and the cable 91 to the right, thus rotating pawl 80 out of contact with the ratchet 74 and the arm 68. This will permit spring 46 to start the louvers 40 toward closed position, and the weight of the louvers 40, actuating rod 44, connecting rod 60, and arm 68 will quickly close the louvers 40. In closed position, the free ends of louvers 40 will overlie the pivot rods 38 of the adjacent louvers, thus obstructing free flow of air.

When the louvers 40 have been in open position, and it is desired to close those louvers, it is only necessary to exert a downward pull on chain 77. That pull will move the arm 68 in a counter-clockwise direction; moving the next shallow notch of ratchet 74 under the free end of pawl 80. Release of that pull will enable spring 46 to start the arm 68 in a clockwise direction; and, because that shallow notch will hold the end of the pawl above the locking shoulder 69 of arm 68, the arm 68 will not be held by pawl 80 and will move to louver-closing position. As the arm 68 moves in a clockwise direction, it will free the switch 75

arm 102 for rotation to "off" position, thus de-energizing motor 32.

The deep and shallow notches in ratchet 74 are circumferentially spaced apart distances which 5 coact with the positioning of pawl 80 relative to slots 54 and 56 to assure the passage of two notches past pawl 80 when arm 68 is moved from closed to open position and to assure the passage of one notch past pawl 80 when arm 68 is moved from open position to the left-hand end of slot 56. Such a construction minimizes the skill required of the operator, and it avoids accidental closing of the louvers.

Whereas a preferred embodiment of the present invention has been shown and described in the drawing and accompanying description, it should be obvious to those skilled in the art that various changes may be made in the form of the invention without affecting the scope thereof.

What I claim is:

1. A louver-operating mechanism that comprises an actuating arm, a linkage which is secured to said arm and to louvers and is movable by said arm to move said louvers, a ratchet carried by said actuating arm, a pivot that rotatably secures said ratchet to said actuating arm, said ratchet having alternate deep and shallow notches, a locking surface on said actuating arm adjacent said ratchet, a pawl disposed intermediate the ends of the path of travel of said actuating arm and disposed to engage said ratchet and said locking surface, said shallow notches being disposable above said locking surface on said actuating arm to hold said pawl above and out of engagement with said locking surface, said deep notches being disposable below said locking surface on said actuating arm to permit said pawl to engage said locking surface, said pawl being adapted to lodge in a deep notch of said ratchet and engage said locking surface of said arm or to lodge in a shallow notch of said ratchet and be held out of engagement with said locking surface on said arm, said shallow and deep notches being alternated around the periphery of said ratchet.

2. A louver-operating mechanism that comprises an actuating arm, a linkage which is secured to said arm and to louvers and is movable by said arm to move said louvers, a ratchet carried by said actuating arm, a pivot that rotatably secures said ratchet to said actuating arm, said ratchet having alternate deep and shallow notches, a locking surface on said actuating arm adjacent said ratchet, a pawl disposed intermediate the ends of the path of travel of said actuating arm and disposed to engage said ratchet and said locking surface, said shallow notches being disposable above said locking surface on said actuating arm to hold said pawl above and out of engagement with said locking surface, said deep notches being disposable below said locking surface on said actuating arm to permit said pawl to engage said locking surface, said pawl being adapted to lodge in a deep notch of said ratchet and engage said locking surface of said arm or to lodge in a shallow notch of said ratchet and be held out of engagement with said locking surface on said arm, said shallow and deep notches being alternated around the periphery of said ratchet.

face on said arm, said shallow and deep notches being alternated around the periphery of said ratchet.

3. A louver-operating mechanism that comprises a plurality of pivots, a plurality of louvers that subtend a predetermined angle in moving from closed to open position, a horizontal frame for supporting said louvers, a rod connecting said louvers for co-ordinated movement, a spring, and an anchor for said spring, said anchor being above and to one side of the pivot for one of said louvers, said anchor and said pivot defining a line that is approximately midway between the open and closed positions of said one louver, one end of said spring being stationary as by being secured to said anchor, the other end of said spring being selectively movable with said one louver to one or the other sides of said line, said spring being distorted when said other end thereof is on said one side of said line, being relaxed when said other end thereof passes through said line, and being again distorted when said other end thereof is on said other side of said line, said other end of said spring being on said one side of said line whenever said louvers are in closed position, being on said line whenever said one louver is approximately midway between closed and open position, and being on said other side of said line whenever said louvers are in open position, whereby said spring applies an initial opening force to said louvers whenever said louvers are in closed position and applies an initial closing force to said louvers whenever said louvers are in open position.

4. A louver-operating mechanism as claimed in claim 3 in which said spring is an elongated helical extension spring, in which said line is spaced from the closed position of said louvers by approximately forty-five degrees, and in which said other end of said spring is secured to said rod adjacent said one louver.

5. In a louver-actuating mechanism the improvement that comprises a movable arm, a linkage that is secured to said movable arm and to louvers, said linkage being movable by said movable arm to move said louvers to open and closed position, a pawl that releasably holds said arm in louver-opening position, said arm being movable from louver-closing position to and past said louver-opening position, a chain, and a spring disposed between said chain and said movable arm, said chain acting through said spring to apply forces to said arm to cause said arm to move from louver-closing to and past louver-opening position, said spring being yieldable to prevent application of undue forces to said movable arm during such movement of said arm.

6. A louver-operating mechanism that comprises an actuating arm, a linkage which is secured to said arm and to louvers and is movable by said arm to move said louvers, a ratchet carried by said actuating arm, a pivot that rotatably secures said ratchet to said actuating arm, said ratchet having alternate deep and shallow notches, a locking surface on said actuating arm adjacent said ratchet, a pawl disposed intermediate the ends of the path of travel of said actuating arm and disposed to engage said ratchet and said locking surface, said shallow notches being disposable above said locking surface on said actuating arm to hold said pawl above and out of engagement with said locking surface, said deep notches being disposable below said locking surface on said actuating arm to permit said pawl to engage said locking surface, said pawl being

adapted to lodge in a deep notch of said ratchet and engage said locking surface of said arm to lodge in a shallow notch of said ratchet and be held out of engagement with said locking surface

5 on said arm, said pawl being so dimensioned and being so disposed adjacent one end of the path of travel of said arm that movement of said arm from closed position to said end of the path of travel will carry two of said notches past said pawl.

7. A louver-operating mechanism that comprises an actuating arm, a linkage which is secured to said arm and to louvers and is movable by said arm to move said louvers, a ratchet carried by said actuating arm, a pivot that rotatably secures said ratchet to said actuating arm, said ratchet having alternate deep and shallow notches, a locking surface on said actuating arm adjacent said ratchet, a pawl disposed intermediate the ends of the path of travel of said actuating arm and disposed to engage said ratchet and said locking surface, said shallow notches being disposable above said locking surface on said actuating arm to hold said pawl above and

20 out of engagement with said locking surface, said deep notches being disposable below said locking surface on said actuating arm to permit said pawl to engage said locking surface, said pawl being adapted to lodge in a deep notch of said

25 ratchet and engage said locking surface of said arm or to lodge in a shallow notch of said ratchet and be held out of engagement with said locking surface on said arm, said pawl being so dimensioned and being so disposed adjacent one end of the path of travel of said arm that movement of said arm from open position to said end of the path of travel will carry one of said notches past said pawl.

8. A louver-operating mechanism that comprises an actuating arm which is movable to move louvers, a ratchet carried by said actuating arm, a pivot that rotatably secures said ratchet to said actuating arm, said ratchet having alternate deep and shallow notches, a locking surface

45 on said actuating arm adjacent said ratchet, a pawl disposed intermediate the ends of the path of travel of said actuating arm and disposed to engage said ratchet and said locking surface, said shallow notches being disposable above said locking surface on said actuating arm to hold said pawl above and out of engagement with said locking surface, said deep notches being disposable below said locking surface on said actuating arm to permit said pawl to engage said locking surface, said pawl being adapted to lodge in a deep notch of said ratchet and engage said locking surface of said arm or to lodge in a shallow notch of said ratchet and be held out of engagement with said locking surface on said arm, a spring adapted to move said pawl out of engagement with said ratchet and said arm, and a heat-responsive element that normally keeps said spring from acting upon said pawl.

9. A louver-operating mechanism that comprises an actuating arm, louvers that open and close in response to movement of said actuating arm, a linkage that is secured to said actuating arm and to said louvers, a locking surface on said arm, a pawl that can selectively engage said locking surface on said arm to hold said arm, and a rotatable ratchet carried by said arm that has deep and shallow notches therein, a pivot that rotatably secures said ratchet to said actuating arm, the deep notches of said ratchet being adapted to permit said pawl to move below the

70 75

level of and into the path of said locking surface on said arm and thereby prevent movement of said actuating arm while the shallow notches of said ratchet are adapted to hold said pawl above and out of the path of said locking surface on said arm and thereby permit movement of said actuating arm, alternate pulls on said arm moving alternate notches of said ratchet against said pawl, thereby causing rotation of said ratchet for alternate presentation of said deep and shallow notches.

10. A louver-operating mechanism that comprises an actuating arm, louvers that open and close in response to movement of said actuating arm, a linkage that is secured to said actuating arm and to said louvers, said linkage being movable by said actuating arm to move said louvers, a locking surface on said arm, a pawl that can selectively engage said locking surface on said arm to hold said arm, and a rotatable ratchet carried by said arm that has deep and shallow notches therein, the deep notches of said ratchet facilitating prevention of movement of said actuating arm by permitting said pawl to pass below the level of and engage said locking surface on said arm, while the shallow notches of said ratchet facilitate movement of said actuating arm by holding said pawl above and out of engagement with said locking surface on said arm; alternate pulls on said arm causing rotation of said ratchet for alternate presentation of said deep and shallow notches, said shallow and deep notches being alternated on the circumference of said ratchet.

11. In a louver-operating mechanism which has a ratchet, a pivot for said ratchet that permits rotation of said ratchet, a pawl engageable with said ratchet, an actuating arm that has a locking surface thereon and that is movable relative to said pawl, and a spring secured to said actuating arm that biases said actuating arm for movement, said actuating arm carrying said pivot for said ratchet and selectively moving said ratchet into engagement with said pawl, said pawl being movable to arm-locking or arm-freeing position with said locking surface, said ratchet having notches of alternate depths to selectively hold said pawl in arm-freeing or arm-locking position, said actuating arm being movable

against the biasing force of said spring to cause relative movement between at least one of the notches of said ratchet and said pawl, said actuating arm being returnable by said spring to cause engagement of said notch and said pawl.

10. A louver-operating mechanism that comprises an actuating arm which is movable to move louvers, a pawl that is pivotally mounted on a stationary part of said louver-operating mechanism and that is adjacent the path of travel of said arm and that is disposed intermediate the ends of said path of travel of said arm, said pawl being engageable with said arm to hold said louvers against movement, a normally distorted spring secured wholly away from said pawl but being inactively attached to said pawl, a normally inactive actuator which can respond to movement of said spring to move said pawl out of engagement with said actuating arm and thereby permit said arm to move, and a heat-responsive link that normally keeps said spring from causing said actuator to move said pawl.

CARL M. BUTTNER.
